UNITED STATES PATENT OFFICE.

HYMAN WANERMAN, OF NEW YORK, N. Y.

DESIGN FOR A LIQUID-REFRESHMENT HOLDER.

Application filed February 16, 1927. Serial No. 20,785. Term of patent 3½ years.

To all whom it may concern:

Be it known that HYMAN WANERMAN, a citizen of the United States, and resident of the borough of Bronx, in the county of Bronx and State of New York, has invented a new, original, and ornamental Design for a Liquid-Refreshment Holder, of which the following is a specification, reference being had to the accompanying drawing, forming part thereof, in which the figure is a perspective view of a liquid-refreshment holder embodying my new design.

I claim:

The ornamental design for a liquid refreshment holder, as shown.

Dated New York, N. Y., February 11th, 1927.

HYMAN WANERMAN.
